US0D1014876S

(12) **United States Design Patent** (10) Patent No.: **US D1,014,876 S**
(45) Date of Patent: ** Feb. 13, 2024

(54) **PET TRACKER CASE**

(71) Applicant: **Lijuan Wang**, Jiangxi (CN)

(72) Inventor: **Lijuan Wang**, Jiangxi (CN)

(**) Term: **15 Years**

(21) Appl. No.: **29/902,507**

(22) Filed: **Sep. 13, 2023**

(51) LOC (14) Cl. **30-99**

(52) U.S. Cl.

USPC **D30/199; D10/104.1**

(57) **CLAIM**

The ornamental design for a pet tracker case, as shown and
described.

DESCRIPTION

FIG. 1 is a perspective view of a pet tracker case showing
my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
